UNITED STATES PATENT OFFICE.

JOHN J. SCHaab, OF ST. LOUIS, MISSOURI.

SAFETY ATTACHMENT FOR GARMENT-POCKETS.

1,268,499.

Specification of Letters Patent. Patented June 4, 1918.

Application filed September 17, 1917. Serial No. 191,784.

To all whom it may concern:

Be it known that I, JOHN J. SCHaab, a citizen of the United States, residing at St. Louis, State of Missouri, have invented certain new and useful Improvements in Safety Attachments for Garment-Pockets, of which the following is a full, clear, and exact description, reference being had to the accompanying drawings, forming a part hereof.

10 My invention has relation to improvements in safety attachments for garment pockets; and it consists in the novel features of construction more fully set forth in the specification and pointed out in the claims.

15 The present is an improvement on the safety attachment for garment pockets forming the subject-matter of my U. S. Patent No. 1,225,863, bearing date of May 15, 1917; and while having the same objects in view and

20 possessing the same advantages as the patented structure, the present improvement possesses the additional advantage in that it can be worn without discomfort by obese persons whose flesh is apt to produce abnormal folds when sitting or stooping, in the region of the waist and groin in proximity to which the conventional trousers pocket is generally located. As its name indicates, the purpose of the attachment is to guard

25 against the loss or unauthorized removal of articles from the pockets of garments, and especially from the pockets of trousers worn by men and boys, the contents of which are ever an easy prey for the pickpocket. The

30 advantages of the improved construction will be fully apparent from the following detailed description in connection with the accompanying drawings in which—

Figure 1 represents a portion of a pair of men's trousers in perspective, showing my invention applied to the side pocket thereof; Fig. 2 is an edge view of the attachment unfolded to conform to the open position of the pocket; Fig. 3 is an edge view of the attachment in its collapsed position and conforming to the closed position of the pocket; Fig. 4 is a combined face view and part transverse section on the zig-zag line 4—4 of Fig. 3; Fig. 5 is an edge view of the attachment in its folded or collapsed position showing the manner in which the same is capable of yielding when in service; Fig. 6 is a plan of one end of the blank from which the intermediate link is formed; Fig. 7 is an edge view of Fig. 6; and Fig. 8 is a perspec-

tive of the slide by which the links of the attachment are controlled.

Referring to the drawings, T, represents a portion of a pair of trousers, and P a conventional side pocket thereof as well understood in the art. The safety attachment herein comprises the terminal pairs of toggle-links 1, 1, the inner ends of the links terminating in reduced extensions 2 which are loosely received between slotted fork terminals 3, 3, of the intermediate links 4, 4. The fork members 3, 3, are formed by first punching an oblong opening o in the blank or strip forming the link 4 (Figs. 6, 7,) after which the metal is folded inwardly on the line α at about the center of the opening, the free end of the folded portion of the strip being then soldered to the main body of the strip beyond the inner terminal of the opening. The soldered (or otherwise fastened) 70 terminal is formed with a shoulder or offset s whereby elongated slots h disposed in the general plane of the strip are formed between the folded and original portions of the metal, said slots loosely receiving the 75 cross pins 5 carried at the free ends of the reduced extensions 2 of the links 1. By this arrangement not only is there effected a hinged connection between the members 1 and 4, but a sliding one as well, the longitudinal extent of the sliding movement being determined by the lengths of the slots h. The pins 5 are flush with the side edges of the links 4. The hinge pin 6 at the meeting 80 ends of the links 1, 1, has its ends projecting slightly beyond the side edges of the links for a purpose presently to appear. The several links connected as described form a 85 collapsible jointed frame which may be opened out as shown in Figs. 1 and 2, or 90 folded to the position shown in Figs. 3, 4, and 5. The links are in the form of flat 95 preferably metallic strips though I do not wish to be restricted to any particular form of cross-section of link or to any specific 100 material. The links 4 are secured to the opposite walls of the pocket by stitching t passed through holes or perforations m and then covered by strips of cloth c if desired.

Traversing the links 1, 1, are slides 7, 105 each slide being formed with an opening or slot w through which the toggle links are passed, and provided with terminal resilient arms or lobes 8, 8, which engage the edges of the links and frictionally maintain the slide 110

on the links at any position to which it may be shifted. At the bases of the lobes 8 are formed recesses or notches *n* for receiving the projecting ends of the hinge pins 6, the 5 said pins limiting the slides in their outward movement, and the notches permitting the slides to be moved to their farthest outward limit to prevent any possible binding action on the links 1, 1, which should 10 be perfectly free to open when the slides are moved to the outer ends of the links.

The operation is simple. When the slides are moved outwardly the frame opens out to allow access into the pocket (Figs. 1 and 15 2). When the slides are moved inwardly or toward the sliding joints between the links 1, and 4, the links 1, 1, are caused to close, thereby forcing the links 4, 4, together and closing the pocket, so that neither can 20 unauthorized persons without detection insert their hands into the pocket, nor can articles in the pocket accidentally drop out of it. The sliding connection formed by the slotted fork members 3, 3, and the cross 25 pins 5, allow the links 1, 1, for a folded or closed position of the frame, to yield in the same direction as shown in Fig. 5, or in opposite directions as shown by the dotted position of one set of links 1, 1, in said 30 figure, depending on the movements of the wearer, and on the manner of the folding of the flesh of the body, obese persons usually causing the terminal links 1, 1, to be forced outwardly (Fig. 5). This simultaneous outward movement of the links 1, 1, under the 35 related circumstances is not permitted by the structure of my patent aforesaid on account of the absence of the sliding connection between the terminal and intermediate 40 set of links. Like the patented structure the improved device may be used in any pertinent connection, and may be composed of more than six links.

Having described my invention what I 45 claim is—

1. A safety attachment for pockets comprising a frame composed of pairs of ter-

50 minal toggle links, a pair of intermediate links pivotally and slidably jointed to the toggle links, slides on the toggle links operating to fold the links together with a movement of the slides toward the intermediate links, and to allow the toggle links to open with a movement of the slides away from the intermediate links.

55 2. A safety attachment for pockets comprising a frame composed of pairs of terminal toggle links having inner reduced ends, a pair of intermediate links terminating in forked members between which said reduced ends are loosely received, said fork members being slotted longitudinally in the general plane of the intermediate link, cross pins carried by the reduced ends of the terminal links and loosely operating in the 60 slots of the slotted fork members aforesaid, and suitable slides on the toggle links for folding the same when moved in one direction, and allowing the links to open when moved in the opposite direction.

65 3. In a device of the character described terminating in toggle links, a hinge pin at the joint between the links projecting at either end beyond the sides of the links, and a slide on the links provided at one end 70 with recesses or notches, to receive the projecting ends of the pin.

75 4. In a device of the character described, a link having fork terminals provided with portions folded against the body of the link 80 from which the fork members spring, the free terminals of the folded portions being provided with offsets engaging the link whereby a slot is formed in each fork member disposed in the general plane of the link, 85 a coöperating link and a pin carried thereby and traversing the slot aforesaid.

In testimony whereof I affix my signature, in presence of two witnesses.

JOHN J. SCHaab.
